SKI BOOT SUPPORT

Johan G. F. Heuvel, 7895 Mountain Sights, Apt. 35,
Montreal, Quebec, Canada

Filed Feb. 24, 1967, Ser. No. 5,938

Term of patent 14 years

(Cl. D34—14)

FIG. 1 is a perspective view of a ski boot support showing my new design;

FIG. 2 is a top plan view of the ski boot support;

FIG. 3 is a side elevational view of FIG. 2;

FIG. 4 is an enlarged fragmentary sectional view taken on the plane of line 4—4 of FIG. 2; and

FIG. 5 is a bottom plan view.

I claim:

The ornamental design for a ski boot support as shown.
